United States Patent Office

Des. 188,504
Patented Aug. 2, 1960

188,504

CULINARY SERVER

Richard S. Latham, Chicago, Ill., assignor to Ekco Products Company, Chicago, Ill., a corporation of Illinois

Filed Mar. 24, 1960, Ser. No. 59,854

Term of patent 14 years

(Cl. D44—29)

Fig. 1 is a front elevation of a culinary server showing my new design.

Fig. 2 is a side elevation thereof.

I claim:

The ornamental design for a culinary server, substantially as shown.
